UNITED STATES PATENT OFFICE

ARLEIGH N. VAN NOSTRAND, OF FLUSHING, NEW YORK, ASSIGNOR TO TELAUTOGRAPH CORPORATION, OF NEW YORK, N. Y., A CORPORATION OF VIRGINIA

STYLUS FOR TELAUTOGRAPHS

Application filed April 5, 1929. Serial No. 352,619.

This invention relates to telautograph transmitting apparatus and more particularly to the stylus and stylus mounting.

The invention aims to provide improvements and refinements in this class of apparatus, such as shown in United States patent to Van Nostrand, No. 1,625,342, granted April 19, 1927.

It is an object of the present invention to 10 reduce wear, thereby to augment the accuracy of transmission and prolong the life of the apparatus.

Another object of the invention is to provide increased flexibility in the stylus 15 mounting to facilitate writing.

A further object of the invention is to simplify the stylus and make the construction more economical, practical, and of fewer parts.

20 With these general objects in view, the invention consists in the features, combinations, details of construction and arrangements of parts which will first be described in connection with the accompanying drawing and then more particularly pointed out.

In the drawing:

Figure 1 is a side view of a stylus constructed in accordance with the invention;

Figure 2 is an enlarged view of details of 30 the apparatus in separated position;

Figure 3 is an exploded view of a fragment of the construction;

Figure 4 is a view of a part of the telautograph apparatus;

35 Figure 5 is a detail view of a portion of the construction.

Referring to the drawing, the invention is exemplified in a stylus which includes a hollow rod 10, having at one end a knob 11, as 40 in Patent No. 1,625,342 referred to. The other end of the rod is adapted to fit over a shank, 10^a, of a member which includes a flange, 12, a tapered portion, 13, extending from the flange, a ball, 14, at the end of the 45 tapered portion, and a stylus point, 16, extending from the ball. This member is preferably composed of a hard, resisting material, such, for example, as a specially treated steel or alloy. A sleeve, 15, of fibre or like 50 material is seated on the rod against flange,

12, and is shrunk firmly in place. This sleeve presents a convenient finger grip.

Means are provided for mounting the stylus in a manner to reduce wear and to permit convenient manipulation in writing. In the 55 embodiment herein shown, the stylus mounting comprises a yoke, 18, having jaws, 19, with cup-shaped members, 20, on the ends thereof facing toward each other. The cup-shaped members are concave and spherical to 60 engage snugly on the ball of the stylus. They are held in place at the ends of the jaws of the yoke by pins 17. The jaws are substantially rigid so as to prevent the ball on the stylus from being pulled out of the 65 cups. In assembling, the cups, 20, are positioned on the ball, the ball and cups are then passed between the jaws of the yoke, and the cups fastened by the pins, 17. The 70 yoke is so designed that the stylus point can swing freely through it without cramping. A limited transverse movement of the stylus is obtained by notching the stylus point as at 16^a for the accommodation of the corners of the cups.

75 The yoke is attached at the end of one arm, 21, of a pair of arms 21, 22. The two arms are pivoted together and to this end the pivoting means disclosed in Patent No. 1,625,342 may be employed. The arm 21 carries a ball 80 25 near the yoke, and the end of arm 22 a yoke 26 having resilient jaws 27 with sockets 28 to receive the ball 25. The jaws press inwardly on the ball to retain it in place, while permitting the arms 21 and 22 to pivot freely 85 with respect to each other. A set screw 29 connects the jaws to prevent their separation and release of the ball 25. The other ends of arms 21, 22, are arranged to engage the respective bell-crank arms of the transmitter 90 rheostat. As this construction is well known, no detailed description is necessary. The connections between the ends of the arms and the transmitter rheostat levers are pivoted 95 connections and may advantageously be similar to the pivoted connections between the arms themselves.

The stylus and stylus mounting of this invention possess important advantages over those shown in the prior patent referred to. 100

The ball 14 has a large bearing surface in the cup-shaped members 20 to reduce the wear on the parts and to distribute wearing uniformly thus to augment the accuracy of transmitted writing. The ball 14 may rotate freely in its yoke and the stylus may pivot freely and universally and may consequently be manipulated conveniently. The free pivotal movement of the stylus provides an increased flexibility over prior apparatus, and a greater ease in writing. In addition, the stylus construction has the advantage of being simple, economical, and of few parts.

What is claimed is:

15. 1. A stylus for telautograph apparatus comprising a yoke on the end of one of the transmitting arms, said yoke having substantially rigid jaws, a pair of separate cup-like members, each flat on one face and having a 20 spherically concave cup at the other face, a stylus having a ball whose radius is the same as the radii of the concave surfaces of the cup-like members, the two cup-like members and the stylus ball in place therein fitting 25 closely the space between the rigid jaws of the yoke, and removable means for fixing each cup-like member to its respective jaw, when the parts have been assembled.
2. A stylus for telautograph apparatus 30 comprising a rod, a flange at one end, a tapering portion extending from the flange, a ball on the end of the tapering portion, a stylus point extending from the ball, and a sleeve on the rod seating against the flange.
35. In testimony whereof, I have hereunto set my hand.

ARLEIGH N. VAN NOSTRAND.
